CARL LINDSTRÖM, OF BERLIN, GERMANY.

MARKING CONTRIVANCE FOR ROLLER STAMPING-MACHINES.

1,230,495.

Specification of Letters Patent. Patented June 19, 1917.

Application filed May 13, 1913. Serial No. 767,372.

To all whom it may concern:

Be it known that I, CARL LINDSTRÖM, a subject of the King of Sweden, residing at Berlin O., Germany, Gr. Frankfurterstr. 137, have invented certain new and useful Improvements in Marking Contrivances for Roller Stamping-Machines, of which the following is a specification.

The invention relates to roller-stamping machines and its object is to provide means whereby stamps can be marked to prevent the same being again used for commercial purposes. The invention is carried out by forming the periphery of the stamp-affixing roller and the periphery of the moistening roller with marking means, such as corrugations, ribs, ridges or the like, so that on a stamp being passed between the rollers the same will receive marks or impressions.

20 In order that my invention may be clearly understood I have hereunto appended drawings, wherein:—

Figure 1 is a perspective view of the marking contrivance.

25 Fig. 2 shows the arrangement of the same on a roller stamping machine and Figs. 3 and 4 are sectional views taken respectively on the lines 3—3 and 4—4 of Fig. 2 and looking in the direction of the arrows.

30 In the drawings 1 is the stamp affixing roller carried by the shaft 2 journaled in the casing 7 and provided with marks, corrugations or ridges 3, while 4 represents the moistening roller rotatably mounted on suitable supports 4^a pivoted at 4^b and controlled by springs 4^c whereby the roller 4 is maintained in surface engagement with the stamp affixing roller 1 adjacent to the marks 3 thereof. The said moistening roller 4 is 35 provided with similar marks, corrugations or ridges 5 arranged in engagement with the marks, corrugations or ridges 3 of the roller 1 and further carries any desired number of annular strips 6 for the purpose of moistening the stamp.

40 The annular strips 6 of the roller 4 may be maintained in a moistened condition in any suitable manner as for instance by engaging a moistening pad 28 suitably supported in the casing 7 and supplied with water in any desired way as for instance from a receptacle located outside of the machine and omitted from the drawings for the sake of clearness. The machine further 45 includes a container 14 located in the casing 7 and in which the strip of stamps 13 in the

form of a roll is rotatably supported, said strip of stamps passing over a table 15 rigidly mounted in the casing 7 and beneath a tension spring 16 carried by said table to 60 the rolls 1 and 4. An arm 17 is pivotally mounted at 17^a in the casing 7 and is maintained in contact with the periphery of a cam 17^b by means of a spring 17^c, said cam 17^b being carried by a shaft 42 rotatably 65 journaled in said casing 7. At its lower end the arm 17 carries a spring pressed pawl or finger 17^d which engages the strip of stamps 13 and serves to feed it between the table 15 and tension spring 16 toward the rollers 1 70 and 4 as will appear more fully hereinafter. A plunger 18 is located over the table 15 and under the influence of an eccentric 18^a carried by the shaft 42 is arranged to periodically press said strip of stamps upon the table 15 whereby the stamp strip is clamped against movement and separation of certain stamp or stamps from the said strip takes place as will be more fully explained further on in the description. An additional roller 80 8 is located beneath the roller 1 and is mounted on a shaft carried by arms 47 secured to a shaft 46 journaled in the casing 7 and carrying a lever 45 the free end of which is provided with a roller 45^a in engagement with a cam 44 also mounted on said shaft 42. A spring 52 serves to maintain the roller 8 in surface engagement with the roller 1 and the marks 3 thereof and at 85 the same time causes the roller 45^a at the free end of the lever 45 to remain in contact with the cam 44. The shaft 42 in addition carries a gear wheel 41 arranged in mesh with a gear wheel 40 located on the shaft 2, whereby rotary motion is transmitted to 90 the roller 1, said shaft 42 being actuated through the medium of an operating crank or handle 43. A table 10 is located adjacent to the rollers 1 and 8 and extends through a slit 9 in the front wall of the casing 7 as 95 100 shown in Fig. 3.

In operation the handle 43 is continuously rotated in the direction of the arrow in Fig. 3 to rotate the shaft 42 and through the medium of the gears 41 and 40 brings about a 105 rotation of the roller 1 which in turn communicates a similar movement to the rollers 4 and 8 owing to the fact that these two rollers are in surface engagement therewith. At the same time the cam 44 will be operated 110 and will actuate the lever 45 and rock the shaft 46 and thus move the roller 8 away.

from the roller 1 against the tension of the spring 52. The rotation of the shaft 42 by means of the handle 43 also brings about an actuation of the cam 17^b so that the arm 17^a is rocked in one direction on its pivot 17^c during which the pawl 17^d slides over the strip of stamps 13 in an inoperative movement toward the right in Fig. 4. As the actuation of the mechanism is continued the cam 17^b will be further rotated and will thus permit the spring 17^e to draw the arm 17 back toward the left in Fig. 4 and the pawl 17^d to engage and feed the stamp strip toward the stamp affixing roller 1 and the roller 4 between which rollers 1 and 4 said strip 13 passes. The stamps pass between said rollers 1 and 4 with the gummed surfaces uppermost and through the coöperation of said rollers are marked and firmly pressed into the marks, corrugations or ridges 3 by the marks 5, while at the same time the gummed surfaces are properly moistened by the moistening strips 6 of the roller 4. In this manner the stamps become firmly affixed upon the corrugations 3 of the roller 1 and are carried along with said roller as rotation thereof continues. In the meantime the envelopes are passed through the slot 9 and are fed along the table 10 between the rollers 1 and 8 which have been separated by the action of the cam 44 on the lever 45, shaft 46 and arms 47. The cam 44 is proportioned so as to maintain the roller 8 out of contact with the roller 1 for a sufficient period to permit the envelopes to become properly positioned between the rollers 1 and 8 to receive the stamp, the spring 52 serving to return the roller 8 into engagement with the roller 1 as soon as the action of the cam 44 on the roller 45^a ceases. The stamps having during this operation been carried along by the roller 1 finally have their moistened, gummed surfaces brought into contact with the envelopes and through the combined action of the rollers 1 and 8 are firmly pressed upon said envelopes and thus caused to adhere thereto. As the mechanism is operated as described the eccentric 18^a will at the proper time cause the plunger 18 to descend and clamp the strip of stamps 13 on the table 15 against further movement until again released through a lifting of said plunger 18. As the strip of stamps 13 is thus held a pull will be exerted on that portion thereof to the left of said plunger 18 in Fig. 4 by the continued rotation of the rollers 1 and 4 and will thus separate a predetermined number of stamps from the strips for application to the envelop or the like. It will of course, be understood that the eccentric is so arranged as to periodically raise and lower the plunger at the proper times to secure the desired results. After the stamps have been properly affixed to the envelop as described the stamped en-

velop is fed along between said rollers 1 and 8 and finally passes down a suitable chute out of the casing 7. The roller 8 firmly presses each successive envelop against the roller 1 and the gummed surfaces of the stamps carried thereby and consequently cause the said stamps to adhere to the envelopes and to be released from the corrugations 3 of the roller 1. In order to keep a correct account of the value of the stamps which have been used in the machine the registering device 11 may be provided. This device is actuated during rotation of the shaft 42 by means of suitable mechanism carried by said shaft, said mechanism being capable of being adjusted or set through the medium of the device 12 which as shown comprises a coöperating notched wheel and spring pressed plunger adapted to be adjusted relatively to each other. According to the adjustment of the mechanism for actuating the device 11, the latter will be tripped one or more times during each rotation of the shaft 42 and will thus add up the amounts of the stamps which are used. For instance the device 11 may be adapted for one cent units, so that if five cent stamps are to be used the mechanism will be set to actuate said device 11 five times during each rotation of the shaft 42 whereby five cents, in one cent units, will be added to the previous total at each operation of said shaft 42.

Various changes in the arrangement shown and described may be made within the scope of the claims without departing from the spirit of my invention.

What I claim is:

1. In a stamping machine, the combination of a moistening roller, a stamping roller, means coöperating with said stamping roller to apply the stamps, means on said rollers for marking said stamps and means for actuating said rollers.
2. In a stamping machine, the combination of a moistening roller, a plurality of ridges on the periphery of said roller for marking stamps, a stamping roller in surface engagement with said moistening roller, means coöperating with said stamping roller to apply said stamps and means for actuating said rollers.
3. In a stamping machine, the combination of a moistening roller, a plurality of ridges on the periphery of said roller for marking stamps, means on said roller for moistening stamps, a stamping roller in surface engagement with said moistening roller, means coöperating with said stamping roller to apply said stamps and means for actuating said rollers.
4. In a stamping machine, the combination of a moistening roller, a plurality of ridges on the periphery of said roller, a stamping roller, a plurality of ridges on the

periphery thereof arranged in engagement with the ridges of said moistening roller for marking stamps, means coöperating with said stamping roller to apply said 5 stamps and means for actuating said rollers.

5. In a stamping machine, the combination of a moistening roller, a plurality of ridges on the periphery of said roller, a plurality of moistening strips on said roller, 10 a stamping roller, a plurality of ridges on the periphery thereof arranged in engagement with the ridges of said moistening roller for marking stamps, means coöperating with said stamping roller to apply said 15 stamps and means for actuating said roller.

6. In a stamping machine, the combination of a moistening roller, a plurality of ridges on the periphery of said roller, a plu-

rality of moistening strips on said roller, a 20 stamping roller, a plurality of ridges on the periphery thereof arranged in engagement with the ridges of said moistening roller for marking stamps, a pressure roller movable toward and away from said stamping roller and arranged to coöperate therewith to apply 25 said stamps, a cam for moving said pressure roller away from said stamping roller and means for actuating said stamping roller and said cam.

In testimony whereof I affix my signature 30 in presence of two witnesses.

CARL LINDSTRÖM.
